ABSTRACT OF THE DISCLOSURE

A package for cartridges, particularly pistol cartridges, with a bottom plate having pegs extending at right angles thereto, which pegs are co-related to the caliber of the cartridges and arranged in aligned rows and columns to form individual storage chambers for the cartridges. The bottom plate may be provided with a rim extending around its circumference and at right angles thereto; the rim and bottom plate may be integrally molded from a synthetic resin. Depressions may be provided in the bottom plate for each of the cartridge chambers to receive therein one axial end of a corresponding cartridge.

BACKGROUND OF THE INVENTION

Various types of packages for cartridges are known. For example, it is known to construct a package similar to a matchbox, having an outer casing receiving therein an internal box in the manner of a drawer. The internal box may be constructed with a bottom, a rim, and a grid insert. Additionally, the package may be closed by means of two insertable tongues, provided on opposite ends of the outer casing.

Another known type of package provides an identical outer casing, but instead of an inner box with a grid insert, a bridge type perforated plate is disposed therein for the suspended arrangement and reception of the cartridges. Additionally, small lugs may be provided on the upper side of the perforated plate to engage the cartridges more firmly.

Also, it is known to provide a package with an internal block with depressions for the reception of the cartridges.

Also, it is known to provide a package box with a bottom section and a lid, if desired a retaining lid, with a grid insert or perforated plate within the bottom section.

All of the above-mentioned constructions have proved to be unsatisfactory, because they are expensive to manufacture and/or a large amount of material is necessary for their manufacture. Moreover, the perforated plate has the additional disadvantage that it can only be utilized for cartridges having a bottom rim.

SUMMARY OF THE INVENTION

It is an object of the present invention to produce a package for cartridges that is simple in its manufacture, of accurate dimensions, and requires very little space for an optimum capacity.

According to the present invention, a package is provided for cartridges, particularly pistol cartridges, wherein a bottom plate is provided with pegs, studs, lugs, spikes or the like extending at right angles thereto and arranged in rows and columns to form therebetween cartridge re-

2

ceiving chambers corresponding in effective cross-sectional areas to the caliber of the cartridges to be received therein. Preferably, the height or length of the pegs is suitably selected so that the cartridges received therebetween and held thereby will extend outwardly beyond the pegs to such an extent that they may be conveniently grasped by hand and removed therefrom.

In a manner similar to the above-mentioned grid insert, the peg plate according to the present invention may be inserted in an inner box received telescopically within an outer casing; in such a case, the peg plate does not have to be provided with a rim. Instead of employing an inner box and an insert separate therefrom, it is contemplated according to the present invention to fashion the peg plate itself as an inner box, by simultaneously constructing the peg plate with the rim, for example, by molding synthetic resin in one piece.

An integral bottom plate with pegs and a rim constructed in such a manner does not have to be inserted in an outer casing only in the manner of a drawer; it is contemplated that a retaining lid, that is a lid having a downwardly extending circumferential rim, may be provided to cooperate with the bottom plate in the manner of a shoe box lid, for example.

In order to obtain optimum dimensions, the height of the bottom plate may be reduced by providing the bottom plate with depressions or perforations extending therethrough between the pegs, for each of the cartridge receiving chambers for receiving therein one axial end of the corresponding cartridge. Not only is the overall height of the cartridge package reduced, but additionally the cartridges are further securely held within the package by the depressions. Advantageously, care is taken with such a construction, utilizing perforations that the cartridges do not stand up with their tips. It is contemplated that the depressions may extend completely through the bottom plate or only partially therethrough; in both cases, it is advantageous to shape the depressions in conformity with the shape of the cartridge tip to be received therein.

A particularly simple and inexpensive manufacturing is obtained if the bottom plate and pegs are constructed as one homogeneous integral piece, for example, by molding from a single blank of synthetic resin. With such a construction, it is particularly simple to adapt the cross-sectional shape of the pegs to the cartridges, particularly if for some reason a circular cross-sectional shape of the pegs is undesirable. Also, it will be simple and advantageous to construct the pegs thicker toward the bottom or with any desired configuration.

Further objects, features and advantages of the present invention will become more clear from the following detailed description of the attached drawing.

BRIEF DESCRIPTION OF THE DRAWING

FIG. 1 shows a bottom plate with pegs according to the present invention;

FIG. 2 shows the bottom peg plate of FIG. 1, together with an external casing;

FIG. 3 shows a peg plate according to the present invention having a rim projecting from its entire circumference;

FIG. 4 illustrates the plate of FIG. 3, partially filled, together with an outer casing for receiving it;

FIGS. 5 and 6 show additional modifications of the peg plate according to the present invention;

FIGS. 7 and 8 show the plates of FIGS. 5 and 6 in corresponding outer casings;

FIG. 9 illustrates a further modification of the bottom plate according to the present invention with a retainer type lid; and

FIG. 10 shows a modification of the FIG. 9 device.

DETAILED DESCRIPTION OF THE DRAWING

As shown in FIG. 1, the bottom plate 1 is provided with a plurality of substantially parallel pegs 2 disposed at right angles thereto. The outermost pegs 2 are uniformly spaced from the edge of the bottom plate 1, so that when the peg plate is inserted in a conventional inner box 3 with a bottom and a rim 4 (FIG. 3), additional cartridges may be inserted between the rim 4 of the box 3 and the outermost pegs 2.

Instead of inserting the peg plate 1, 2 into a special inner box 3 according to FIG. 3 and subsequently inserting this combination into an external casing 5 (FIG. 2), it is contemplated that the peg plate 1, 2 may be directly inserted into the outer casing 5. If the peg plate is inserted directly into the outer casing 5, the cartridges may then be received only within the cartridge chambers formed by the pegs; this would be in contrast to the insertion of cartridges between the outermost pegs and the rim 4 as shown in FIG. 3.

In contrast to inserting the bottom plate 1 with the pegs 2 into an inner box 3, it is contemplated according to the present invention to construct the bottom plate 1, pegs 2, and inner box 3 of a single piece, for example, by molding a synthetic resin. Such a construction would be extremely simple with a synthetic resin, which can be molded easily and advantageously into a great variety of shapes according to many different methods. The box of FIG. 4, partially filled with cartridges 6, may be considered as an inner box 3 with the bottom plate 1 having pegs 2 inserted therein, or it may be considered as an integral construction; in the latter case, there will be no double bottom so that a corresponding simplicity and reduction in dimensions is obtained. In both cases, the packaging may be completed by providing the outer casing 5.

In the embodiments of FIGS. 5 and 6, no outer edge is provided for the bottom piece 1 having the pegs 2. The bottom plate may be square as shown in FIG. 5, or it may be rectangular as shown in FIG. 6. In either case, the pegs 2 are provided along the outer edge portion of the bottom plate 1. As may be seen with respect to FIG. 5, for example, the outer pegs 2 may be weaker in their cross-section than the inner pegs 2, which is understood when it is realized that these outer pegs could be replaced by a thin walled rim extending around the plate to satisfactorily retain the outermost cartridges.

The spacing between the individual pegs is correlated to the caliber of the cartridges so that the cartridges may be guided and securely supported therebetween, while at the same time assure the easy removal of the cartridges. These advantages are obtained by appropriately constructing the pegs of a suitable shape, height and spacing. In this connection, it is contemplated that the pegs may have a cross-sectional shape quite different from the illustrated circular cross-sectional shape, for example, the pegs may be conically constructed or otherwise thickened toward the bottom plate 1.

The bottom plates according to FIGS. 5 and 6 are different from the bottom plates according to FIGS. 1-5 in that they have perforations 7 between the pegs 2. It is particularly desirable that these perforations 7 do not allow the cartridge tips to extend therethrough below the lowermost surface of the bottom plate 1, which would prevent or hinder the insertion of the bottom plate 1 into the outer casing 5 (FIGS. 7 and 8), particularly if the bottom plate 1 is freely supported. To provide for particularly secure support and guidance of the cartridges while at the same time providing a minimum of material

to be used in the construction of the package, it is particularly desirable to construct the perforations so that the tips of the cartridges will be flush with the outer bottom wall of the bottom plate 1.

Even in the case of the bottom plate 1 with the pegs 2, according to FIG. 9, where the retaining lid 8 is dropped thereover, the above considerations apply with respect to the perforation 7. As shown in FIG. 9, it is desirable to provide the bottom plate 1 with an edge 9 for receiving the retaining lid 8.

As shown in FIG. 10, the edge of the retaining lid of FIG. 9 is practically combined with the bottom plate 1. The construction of FIG. 10 is similar to the construction of FIG. 9, in that the bottom plate 1 is provided with only depressions and not with holes extending all the way therethrough so that a fool-proof, secure package is obtained that will prevent damage to the cartridges by dirt or blows. With this construction, it is also possible to form the bottom plate, pegs, and inner box of a single, one piece construction, as well as constructing these elements as individual portions.

Instead of constructing the lid 10 as shown, it may also be constructed as a retaining lid, with a depending rim or edge around its periphery extending along a shoulder or rim of the bottom plate.

Further modifications are contemplated and many different types of materials may be employed according to the broader aspects of the present invention. It is particularly advantageous to construct the peg plates 1, 2 of a synthetic resin, particularly when molding it as a single piece, instead of providing a separate inner box, with a molded rim replacing the inner box. A separate inner box might be constructed of cardboard.

According to the broader aspects of the present invention, the package is not limited to any specific type of cartridge or any particular caliber of cartridge. For example, the package may be used to store cartridges that do not have a projecting bottom rim or flange.

All of the bottom plates 1 shown in FIGS. 1-10, may be provided with depressions extending partially therethrough or holes extending all the way therethrough for receiving the tips of the cartridges. It is contemplated that the constructions according to FIGS. 1-10 may be either multi-piece constructions or single piece constructions with respect to the bottom plate 1, pegs 2 and any rims.

Although specific preferred forms of the present invention have been disclosed with respect to their particularly advantageous specific details, further modifications, variations and embodiments are contemplated.

We claim:

1. A cartridge package, comprising: a plurality of explosive propellant-containing cartridges each having a rear primer end and an opposite forward tip, a bottom plate; a plurality of substantially parallel pegs extending at right angles to and being integral with said bottom plate in aligned rows and columns, said pegs being dimensioned and spaced apart forming uniform parallel chambers securely supporting and guiding said cartridges therein, said chambers conforming to the caliber of said cartridges, said bottom plate being provided with at least one depression between said pegs receiving the forward tip of a corresponding cartridge, so that said cartridges do not stand on said forward tips.

2. The package according to claim 1, including an outer, upstanding rim extending around the outer circumference of, being integral with and extending at right angles to said bottom plate.

3. The package according to claim 2, wherein said bottom plate pegs, and rim are fabricated from a molded synthetic resin.

4. The package according to claim 3, wherein the outermost ones of said pegs are inwardly spaced from said rim to form cartridge receiving chambers between adjacent pegs and said rim.

3,525,425

6

5. The package according to claim 1, including a container enclosing said integrally-molded bottom plate and said plurality of pegs.
